Primary Examiner — Vy Koenig*(74) Attorney, Agent, or Firm* — Pearne & Gordon LLP**(57) CLAIM**

The ornamental design for a packaging, as shown and described.

DESCRIPTION

FIG. 1 is a front-left perspective view of a first embodiment of a packaging, showing our new design;
 FIG. 2 is a front elevational view thereof;
 FIG. 3 is a right side elevational view thereof;
 FIG. 4 is a back elevational view thereof;
 FIG. 5 is a left side elevational view thereof;
 FIG. 6 is a top plan view thereof;
 FIG. 7 is a bottom plan view thereof;
 FIG. 8 is a front-left perspective view of a second embodiment of a packaging, according to the invention;
 FIG. 9 is a front elevational view thereof;
 FIG. 10 is a right side elevational view thereof;
 FIG. 11 is a back elevational view thereof;
 FIG. 12 is a left side elevational view thereof;
 FIG. 13 is a top plan view thereof; and,
 FIG. 14 is a bottom plan view thereof.
